US00D975501S

(12) **United States Design Patent** (10) Patent No.: **US D975,501 S**
(45) Date of Patent: **** Jan. 17, 2023**

(54) **INSULATING DEVICE**

(71) Applicant: **YETI Coolers, LLC**, Austin, TX (US)

(72) Inventors: **Roy Joseph Seiders**, Austin, TX (US); **Derek G. Sullivan**, Austin, TX (US); **Erik Steven Larson**, Austin, TX (US); **Alex Baires**, Austin, TX (US)

(73) Assignee: **YETI Coolers, LLC**, Austin, TX (US)

(***) Term: **15 Years**

(21) Appl. No.: **29/804,804**

(22) Filed: **Aug. 23, 2021**

Related U.S. Application Data

(63) Continuation of application No. 29/755,364, filed on Oct. 20, 2020, now Pat. No. Des. 956,481, which is a continuation of application No. 29/732,997, filed on Apr. 29, 2020, now Pat. No. Des. 899,197, which is a continuation of application No. 29/703,095, filed on Aug. 23, 2019, now Pat. No. Des. 896,591, which is

(57) **CLAIM**

The ornamental design for an insulating device, as shown and described.

DESCRIPTION

FIG. 1 is a top, front, left perspective view of an insulating device showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dot-dash lines represent unclaimed boundaries. The zig-zag broken lines represent zipper teeth and form no part of the claimed design. The even-length broken lines form no part of the claimed design.

1 Claim, 7 Drawing Sheets

Related U.S. Application Data

a continuation of application No. 29/624,126, filed on Oct. 30, 2017, now Pat. No. Des. 862,177, which is a continuation of application No. 29/553,995, filed on Feb. 5, 2016, now Pat. No. Des. 801,123.
